UNITED STATES PATENT OFFICE.

ALBERT W. NEITRO, OF SEATTLE, WASHINGTON.

ELECTROTHERAPEUTICAL APPARATUS.

1,051,349.

Specification of Letters Patent.

Patented Jan. 21, 1913.

Application filed July 11, 1910. Serial No. 571,538.

To all whom it may concern:

Be it known that I, ALBERT W. NEITRO, a citizen of the United States of America, residing at No. 1610 Eighteenth avenue, in 5 the city of Seattle, county of King, State of Washington, have invented a new and useful Apparatus or Machine, which I have entitled "Electrotatherapeutical Apparatus," of which the following is a specification.

10 My invention relates to electro-therapeutic devices, or devices which employ electricity, light and heat in their various forms as agencies for the beneficial treatment of the human body for the relief and cure of 15 ailments to which it is subjected. My device is equally beneficial in its result upon the nerves and mental condition of the patient as upon his physical condition.

In the drawings I have shown my invention in the form which is now preferred by me.

Figure 1 shows my device in perspective, from the head end, the couch and the body of the patient being within the casing. Fig. 25 2 is a perspective from the same end but viewed from the opposite side, the couch being withdrawn. Fig. 3 is a longitudinal, sectional elevation, the couch being within the casing. Fig. 4 is an elevation of the 30 head end of the device. Fig. 5 is a longitudinal sectional plan, the plane of the section being above the couch, which is within the casing. Fig. 6 is a transverse sectional view.

35 The construction of my device as embodied in the preferred form shown in these drawings is as follows. I provide a casing or outer shell of such length that it will receive the prone body of the patient, and 40 of a diameter such as will receive a couch and the patient thereon and also provide ample room for the therapeutic apparatus by which the electrical, light and heat effects are produced. This casing 5, is pref- 45 erably made of an insulating material, for which purpose wood is satisfactory. I have shown this casing as of an octagonal shape, the ends being closed except that provision is made at the head end for the entrance 50 of the couch and patient, and doors are provided at the foot end for convenience in manipulating and caring for the apparatus employed. The opening at the head end may be closed when desired by one or both 55 of two curtains 7^a and 7^b, the former being inward from the latter and herein shown

as provided with button holes 7^c adapted to be engaged with buttons secured to the casing head. The other curtain 7^b, is herein shown as rolling up after the manner of the common window shades. These curtains have notches in their lower edge, adapted to fit about the neck of the patient so that the head may be permitted to remain outside the cabinet and not subjected to the influences applied to the body. Upon the inner surface of each of the octagonal faces is placed a mirror or mirrors 4, which mirrors are so shaped and placed, that each section is, as a whole, convex inwardly, thus forming sections of cylindrical or prismatic surfaces extending lengthwise the chamber. These mirrors, as shown, consist of segments of cylindrical surfaces. Between these mirrors are thus formed valleys or troughs, 75 in which are placed electric lights 12 and electrodes 15. The lights 12 may be any type or combinations of types which it may be desired to use, their choice being determined by the effect produced by the different types and the result desired in the particular case. These electric lamps may be connected up in different circuits, so that a single type or a combination of more than one type may be used at the same time, as 80 desired. I also provide lamps and electrodes of corresponding character and variety at the ends of the casing. I also provide a certain number of these lights, as 12, located at the end, or wherever may be 85 most convenient, with screens or slides 12^a of colored glass, which may be removed and changed as desired. In this way treatment with different colored light may be given. I also provide switches by which 90 the application and distribution of the electricity may be controlled.

In each valley or trough, I place a series of electrodes or electrical discharging points 14, which are used in connection with a 100 galvanic battery or other source of high tension electricity, either directly, or through the intermediation of a coil or other transformer device, so that discharges of static or galvanic electricity may be produced within the chamber and the patient may be subjected to the influences of electric vibrations of high tension. The patient when under treatment lies within the center of an area which is saturated with these 105 high tension electric waves. These static electrodes are so connected with the source 110

of electric energy that a row of positively charged points is opposite a row of negatively charged points upon the opposite sides of the chamber. The positive electrodes are preferably in adjacent rows extending about one half the interior surface of the casings and the negative electrodes extend about the other half. The patient, whose body occupies the longitudinal axis 10 of the chamber, is thus in the axis of the field of force produced by these discharges. Within the chamber is a trackway 2, adjacent and parallel with the axis of the chamber. Upon this trackway travels a couch, 15 or body support 1, the two being so proportioned and located that the body of the patient will occupy substantially the axis of the chamber when lying upon the couch 1. This trackway extends slightly without the 20 head end of the chamber and exterior thereto is provided with supporting legs 3 extending to the floor. Between the side bars of the couch 1 is constructed or supported a net work of webs or straps 17, so placed 25 as to form an open work support for the body, thus contributing to the comfort and complete relaxation of both the physical body and the mind, in which condition the patient is most susceptible to the beneficial 30 influences.

The couch is supported upon the trackway by wheels 18, which may be mounted upon either the trackway or the couch. I have shown them as upon the couch. The 35 outer or head end of the couch has depending legs 1', provided at their lower end with rollers 20, engaging and rolling upon the floor. This end is also provided with a head rest 19, adjustable in height and 40 angle, by means of the perforated segment bars 21 and pins which may be inserted in any one of the holes in the bars. At each side of the couch near its foot, is a standard 44, which carries a bar 43, which extends 45 lengthwise the couch and may be adjusted in said standard to vary its position. The

forward or free end of these rods carry plates 9, adapted to serve as terminals for galvanic or induced currents and to be engaged by the feet of the patient. The use 50 of these is at all times under complete control of the patient. The couch is provided with contact members 10 and 11, at its head end, and the end of the casing, or any other suitable stationary member, is provided with complementary contact members 55 10' and 11', in position to be engaged by the members 10 and 11 when the couch is rolled into place within the casing. The terminals 9 are connected with the contact members 60 10 and hand electrodes 8 are connected with the terminals 11, whereby the patient is able to apply the electric current to any part of the body. This application may be made lightly or with force as desired. 65

What I claim as my invention is:

In an electro-therapeutical apparatus, in combination, a casing forming a chamber adapted to receive a prone body, a series of light reflectors extending lengthwise the 70 chamber and carried upon its inner walls, said reflectors being disposed to form inwardly convex ridges and concave valleys or troughs extending lengthwise the casing, electric lights and discharge-producing elec- 75 trodes alternating with each other and occupying said valleys or troughs, means for controlling the energization of said lights and discharge-producing electrodes, a trackway extending lengthwise the chamber adja- 80 cent its axis, a couch adapted to travel in and out upon said trackway and having downwardly extending legs exterior to the casing and engaging the floor, and contact electrodes carried by said couch and adapted 85 to apply electricity to different parts of the body.

ALBERT W. NEITRO.
